United States Patent

Des. 238,574
Patented Jan. 27, 1976

238,574

ENVELOPE

Charles S. Watson, Glen Ridge, N.J., assignor to Berlin & Jones Company, Inc., East Rutherford, N.J.

Filed Sept. 27, 1973, Ser. No. 401,202

Term of patent 14 years

Int. Cl. D19—01

U.S. Cl. D19—3

FIG. 1

FIG. 2

FIG. 3

FIG. 4

FIG. 5

FIG. 6

FIG. 7

FIG. 1 is a back elevational view of an envelope showing my new design in closed position;

FIG. 2 is a front elevational view thereof;

FIG. 3 is an inside perspective view in open position;

FIG. 4 is a back elevational view with only one flap in open position;

FIG. 5 is a view thereof with two flaps in open position;

FIG. 6 is a view with three flaps open; and

FIG. 7 is an inside plan view of the envelope.

I claim:
An original design for an envelope, as shown.
